(57) CLAIM

The ornamental design for a grave caddy, as shown and described.

DESCRIPTION

FIG. 1 is a perspective view of a grave caddy showing my new design;

FIG. 2 is a front view thereof;

FIG. 3 is a right side elevational view thereof, the left side being a mirror image thereof;

FIG. 4 is a top view thereof;

FIG. 5 is a bottom view thereof; and,

FIG. 6 is a rear view thereof.

The broken line showing of the marker is for illustrative purposes only and forms no part of the claimed design.
